UNITED STATES PATENT OFFICE.

LOUIS GOLDNER, OF BROOKLYN, NEW YORK.

SPATTEE.

Application filed December 31, 1926. Serial No. 158,378.

This invention relates to garments and particularly to an improved covering for the lower part of the leg, the same being known generally as a spattee, the object being to provide an improved structure wherein a pleasing garment is produced and means provided at the lower end for holding the parts in a correct knit position.

Another object is to provide in a spattee 10 or similar garment a protecting and holding member of elastic material formed partly of rubber and arranged adjacent the toe section for protecting the foot against rain and the like and at the same time holding the exposed 15 part of the garment in substantially its original shape.

A further object of the invention is to provide a spattee with a stiffening and reinforcing member at the toe section loosely 20 engaging the spattee except at the point of connection and acting to resist any stretching of the spattee at this point as well as protect the foot against rain, snow and the like.

In the accompanying drawing—

25 Figure 1 is a perspective view of a spattee disclosing an embodiment of the invention, the same being shown applied.

Figure 2 is a rear perspective view of the 30 spattee shown in Figure 1, the same being on a slightly reduced scale.

Figure 3 is an enlarged vertical sectional view through the lower part of the spattee shown in Figure 1.

Figure 4 is a transverse sectional view 35 through Figure 3 approximately on line 3—3.

Referring to the accompanying drawing by numerals, 1 indicates the body of a spattee which merges into a forward or toe section 2 and also a rear or heel section 3. The body 40 1 is formed of knit material capable of stretching transversely and formed to slip on over the end of the foot and be held in place by the resilient action of the material. At the bottom edge, the material of body 1 and sections 2 and 3 is turned up to form an inner flange 4 which is covered by a protecting strip 5 of substantially inelastic tape held in place by suitable lines of stitching 6. This tape stiffens and prevents stretching of 45 the lower part of the spattee and also causes the same to snugly fit the foot as indicated.

in Figures 1 and 2. A strap 7 is provided which may be leather or other material and may be made in one piece as shown particularly in Figure 4 or made in two pieces 55 and connected by a buckle or other means. Arranged interiorly of the forward or toe section 2 is a supporting and protecting member 8 held in place by the stitching 6 and conforming to the shape of the section 2. Preferably, the member 8 loosely fits within the section 2 except at the point where it is stitched in place whereby any strain brought to bear on the forward part of the spattee will be first taken up by member 8 and later 60 communicated to section 2 if the distention of the parts is considerable. The member 8 is woven or knit fabric and is formed partly of rubber strands whereby it will resist to an appreciable extent the distention though permitting such distention when necessary. The member 8 may be an ordinary elastic 65 now commonly used on the market or may be made specially strong as preferred. Preferably, the member 8 extends to the upper part 70 of the instep, though it could be made longer if desired.

When the spattee has been completed and is ready for the market, it is pressed so as to give a smooth appearance and when first 80 used will have a crease 9 which naturally indicates newness and presents a very neat structure. As it is desired in the use of the spattee to retain this new appearance and neatness as long as possible, the member 8 is 85 arranged at a point to take care of any strain or distention of the parts, thus relieving the section 2 of such strain and, consequently, permitting the seam 9 to remain in place for a long time. In addition, the member 8 is 90 substantially waterproof and, consequently, will protect the foot against water or snow splashed on the foot during walking.

What I claim is:

1. A spattee comprising a stretchable body merging into a heel section and toe section, a reinforcing and stiffening member stitched to the lower edge of the spattee on the interior thereof, and a member stitched to said front section and loosely fitting the same for protecting the same against undue distortion. 95
2. A spattee comprising a stretchable body 100

merging into a heel section and toe section, and a stiffening, reinforcing and protecting member stitched to the lower part of said toe section, said member being formed partly of 5 rubber and partly of fabric.

3. A spattee comprising a knit body merging into a knit heel and toe section, a member fitting within said toe section, and a line

of stitching arranged along the lower edge 10 of said member and said toe section for connecting the toe section and member together, said member being formed of rubber and fabric yarns whereby the member will protect the foot against water and will protect the toe section against undue distention.

LOUIS GOLDNER.
